UNITED STATES PATENT OFFICE.

JOHN R. CARTER, OF TORONTO, ONTARIO, CANADA.

MANIFOLD COPYING-BOOK.

SPECIFICATION forming part of Letters Patent No. 252,646, dated January 24, 1882.

Application filed November 8, 1881. (No model.)

To all whom it may concern:

Be it known that I, JOHN ROBERT CARTER, of the city of Toronto, in the county of York, in the Province of Ontario, Canada, have invented certain new and useful Improvements in Manifold Copying-Books, of which the following is a specification.

The object of the invention is to provide a check-book in which the black leaf used for transferring writing from one page to another need not be handled and will not have a tendency to curl up after a number of leaves have been torn out; and it consists, essentially, of a black-leaf check-book composed of double leaves, one half of which are bound together, while the other half are folded in as fly-leaves, both being perforated across, so that they can be readily torn out, the black leaf being bound into the book next to the cover and provided with a tape bound across its end, the said black leaf having the transferring composition on one of its sides only.

The drawing represents my black-leaf check-book, the cover being held open by one hand, the fly-leaf being raised by another, and the black leaf folded back, so as to show the transferring composition on its bottom side.

A is the cover of the book. B is a fly-leaf attached to or forming part of the leaf C. The leaves B and C are separated by perforations running across the crease. Similar perforations running across the leaves C, near the binding, enable this latter leaf to be torn out, leaving only a stub, D.

E is the black leaf, bound with the other leaves, but next to the cover A. This leaf has a transferring composition on its under side only, and is provided with a tape, F, bound across its lower end, as shown. This tape enables the black leaf to be folded back or raised without soiling the fingers. When the book is about to be used the black leaf E is laid flat upon the face of the leaf C, the transferring

composition on the under side of the leaf E resting on the face of the leaf C. The leaf B 45 is then allowed to rest on top of the black leaf E, and when the necessary memorandum is written upon the leaf B it is transferred onto the leaf C. The leaf B may then be torn from the leaf C and the latter leaf removed from the 50 stub. A double leaf corresponding with B and C will then be exposed and the operation repeated, as described.

It will be seen that a book made in this manner will be less bulky than if all the leaves 55 were bound into the stub, and there would be less likelihood of the black leaf becoming crumpled up than if it were placed in the center and the leaves removed from the stub on either side.

I am aware that black leaves are used in other forms of books used in transferring writing from one page to another; but they are either loose in the book, and are therefore easily lost and are dirty to handle, or are placed in 65 the center of the book and the leaves numbered on either side of it, which latter arrangement is faulty from the fact that the space left on each side of the black leaf when the leaves are torn out causes the black leaf to curl up 70 and become unsatisfactory in its operation.

What I claim as my invention is—

A black-leaf check-book composed of double leaves, one half of which are bound together, while the other half fold in as fly-leaves, both 75 being perforated across, so that they can readily be torn out, and the black leaf bound into the book next to the cover, and provided with the tape secured across its end, the said black leaf having the transferring composition on one 80 of its sides only.

JNO. R. CARTER.
